UNITED STATES PATENT OFFICE

SAMUEL E. HITT, OF ELYRIA, OHIO

PROPELLION AND STEERING OF AEROSHIPS

Application filed March 26, 1929. Serial No. 349,916.

This invention relates to means for the propulsion and steering of aeroships, whether on the water or in the air and is particularly adaptable to the aeroship described and shown in my application filed March 26th, 1928, for air and water craft, Serial No. 264,634.

The objects of the invention are as follows:—

10 To provide electric propulsion units for the propulsion of the aeroship.

To provide electric propulsion units for steering the aeroship.

15 To provide turntable mountings for the propulsion units, so that all the propellers can be turned to head into the wind or toward the head resistance or at such angle between the two according to relative velocity of ship and wind, as will perfectly equalize those forces 20 and cause the aeroship to maintain a course straight ahead without drift.

To provide separate controls for the fore and aft propulsion units, by which the fore units can be turned to star-board and the aft 25 units to port or vice versa to steer the aeroship when on the water or in the air.

30 To provide an aeroship with propulsion units placed between the wing and hull resistance in such manner as to reduce the strains upon the frames.

To provide propulsion units on both the inner and outer sides of the hull frames to balance the load on the hulls.

35 To provide electric motor drives for all propellers of the propulsion units.

To provide a propulsion unit pivotedly mounted upon a post or column to elevate it above the deck, so that the propeller will clear the deck and so that the propeller will be 40 clear of slip stream interference from the framework of the aeroship.

To provide an electric motor drive for the turntable mounting of the steering unit applicable to one or more units, located either 45 forward or aft.

To provide an electric motor drive for the turntable mounting of the propulsion units, applicable to any number of units located between the fore and aft steering units.

To provide a source of power in the power house for all the propulsion units.

To provide control of all propulsion units in the pilot house.

To provide the pilot house with a switch 55 board for the propulsion units.

To provide the pilot house with a switch board for the steering units.

To provide a steering wheel or helm to operate the controllers for the electric motors 60 which turn the fore and aft propulsion units to steer the aeroship.

To provide the switch board with ammeters for each electric motor to indicate whether the motor is running and the amount of current being used.

To provide the switch board with individual switches so that any one of the motors can be cut out of service.

To provide group switches so that propulsion units on either hull can be operated separately.

To provide group switches so that any line of propulsion units on the inner or outer sides of either hulls can be operated separately.

To provide group switches so that propulsion units fore and aft can be operated separately.

To provide a main switch for all propulsion units.

To provide a separate control board for the steering units.

With the above and other objects in view, the invention further includes the following novel features and details of construction, to be hereinafter more fully described, illustrated in the accompanying drawings and pointed out in the appended claims.

In the drawings:—

Fig. 1 is an end view of my aeroship.

Fig. 2 is a plan of a fore and aft line of propulsion units.

Fig. 3 is an elevation of the propulsion unit.

Fig. 4 is a plan of the same.

Fig. 5 is a sectional elevation of the upper portion of the propeller and motor support.

Fig. 6 is a sectional elevation of the lower portion of same.

Fig. 7 is a plan of the aero ship.

Fig. 8 is a diagram of the propulsion units.

Fig. 9 is the switch board.

Fig. 10 is the steering control board.

5 Referring to the drawings in detail, wherein like characters of reference denote corresponding parts, in Fig. 1, the port hull 1 carries a superstructure 3—25, masts 9, wings 10 and propulsion units 210 and 211.

10 The starboard hull 2 carries the superstructure 4—26, masts 9', wings 10' and propulsion units 220 and 221. The hull units 1 and 2 are connected by the bridge 5 and spanner 7.

15 Generally, the aero ship is symmetrical about the center, both fore and aft and also abeam and can go backwards as well as forward.

Propulsion units 210 and 211 are placed 20 on the upper deck 17 over hull 1 on the inner and outer sides to be clear of slip stream 25 interference from masts 9.

In like manner, propulsion units 220 and 221 are placed on the inner and outer edges 25 of deck 17' over hull 2 to be clear of interference from masts 9'.

21 is the pilot house.

22 is the power house.

23 is the searchlight.

30 The pilot house 21 is shown over the power house 22. In the pilot house 205 is the helm for steering. In the power house, 230 is the electric generator with leads 231 for current supply to the propulsion units.

35 In Fig. 3, the propulsion and steering unit is shown in elevation supported on the upper deck 17 of the main frame 3 and 4. 100 is the propeller, 101 the propulsion motor, 102 pinion and 103 gear for turning the unit in 40 any direction, 104 shaft, 105 and 106 bearings, 107 worm and 108 worm wheel for intermediate gear reduction, 109 worm shaft, 111 electric motor, 112 the slip stream shield for electric motor, and 119a a motor gear bearing.

45 In Fig. 4, a plan of the propulsion and steering unit gearing, 114 is the motor pinion, 115 is the motor gear, and 110 the worm shaft bearings.

50 In Figs. 5 and 6, the propulsion unit is shown supported on the upper deck 17 by base 120, post 121, hollow shaft 122, bearing 123, seat 124, and balls 125. 110 are the worm shaft bearings, supported by brackets 127 on the base 120. 128 is the cover over the worm gearing.

55 Fig. 2 shows one line of propulsion and steering units extending fore and aft. 130 is the fore unit and 131 the aft unit, both under separate control of the pilot. The unit 130 is shown turned to starboard and the unit 131 to port, for turning the aero ship to starboard.

60 65 The intermediate units 132 are turned by

one electric motor 133 and are under one control in the cabin.

To steer straight ahead, all motors are brought to the same angle, necessary to accomplish that result. That angle is determined by the pilot and depends on the direction and velocity of both the aero ship and the prevailing wind. In a dead calm, the motor units are turned straight ahead.

70 For the purpose of reducing the size of 75 unit and to balance the load on the hulls, I prefer the alternate arrangement shown in Figs. 1, 7 and 8 where the propulsion units are on the inner and outer sides of hulls 1 and 2 and for which provision is made in 80 the switch board shown in Fig. 9.

In Fig. 7, four lines of propulsion units 210, 211, 220 and 221 are shown on the inner and outer edges of frames 3 and 4 over hulls 1 and 2, each line of units similar to that 85 shown in more detail in Fig. 8.

Fig. 8 is a diagram showing in plan the turning drives for all of the propulsion and steering units in which shaft 240 turns the inner units 210 and the shaft 241 turns the 90 outer units 211 over hull 1. Shafts 240 and 241 are driven by one motor 243 through cross shafting 244 and bevel gears 245.

In like manner on hull 2, the inner and outer propulsion units 220 and 221 are turned by the shafts 246 and 247 driven by one motor 248 through cross shafting 249 and bevel gears 250.

The fore and aft steering units on hulls 1 and 2 are all the same, the units 130 and 130a 100 driven by the cross shafting 251 and electric motor 252. The aft units 131 and 131a are turned in a similar manner by one motor 253.

The control board in Fig. 10 is the same 105 for either two or four lines of propulsion units.

Fig. 9 shows the current control board for 110 all of the propulsion units, including the steering units. 150 are indicators to show whether the numerous propulsion motors are running or not, one for each unit with its individual switch 151. Switch 151 controls a propulsion motor forward on the outboard side of the port hull 1 and switch 152 on the inner side. Switch 153 controls a propulsion 115 motor aft on the outboard side of port hull 1 and switch 154 the inner side.

In a similar manner, switches 155, 156, 157 and 158 control the propulsion motors fore and aft on hull 2.

120 Switch 159 controls all the propeller motors forward on port hull 1, switch 160 all the units aft on hull 1. Switch 161 all the propeller motors forward on starboard hull 2 and 162 all the units aft. 163 is a main switch and controls all the propeller motors.

125 In Fig. 10 control board for steering motors 170 is an indicator showing the angular position of the fore steering units 130 of the port hull 1 and 171 is the controller for the 130

motors 234 for turning those units, the handle 178 turned to the left to steer to port and to the right to steer to starboard.

In like manner 172 is the indicator and 173 5 is the controller for the aft steering motors 235 of hull 1.

In like manner also, indicator 174 and controller 175, indicator 176 and controller 177 are for the fore and aft steering motors 10 of the starboard hull 2. Ordinarily the controllers 171, 173, 175 and 177 are geared to the helm, but may be disconnected and operated separately.

The two central panels in Fig. 10 are for 15 turning the intermediate propulsion units and control all the four groups 210, 211, 220 and 221. Indicator 179 and controller 180 are for groups 210 and 211 on hull 1. Indicator 181 and controller 182 are for groups 20 220 and 221 on hull 2.

The pilot at the helm, has a double wheel, one for turning the steering units and one for turning the intermediate units. He also has before him a set of indicators, such as 170, 25 179 and 176 for line of units 210 shown on control board in Fig. 10. With the two wheels the pilot operates all the propulsion units and the attendant at the board makes frequent adjustments to keep all four lines 30 of units in unison. In other words, he watches the control board to see that all the forward steering units turn together, all the aft units turn together and all the intermediate units turn together.

35 The operation of my invention is as follows:—

On leaving harbor, when clear in the open, the pilot proceeds to turn the aeroplane to the course mapped out.

40 By a glance at the indicators before him, the pilot knows the angular position of each group. By operation of the electric controllers for the electric motors of the fore unit 180 and the aft unit 131, the units 130 45 turn to face starboard and units 131 to face port, or vice versa, the aeroplane comes about until on the right course, when all the propulsion units are adjusted to hold the course.

The end units 130 and 131 are brought to 50 face in the same direction as the intermediate units 132, the facing angle or deviation from course depending on the relative directions of the aeroplane and the prevailing wind and also on the speed of the aeroplane relative to 55 the velocity of the wind. Position of propulsion units therefore must be frequently adjusted until the aeroplane gets up to speed. The pilot then checks up to see if he is holding his course.

60 On starting out, the velocity of the wind may be great in comparison with the speed of the aeroplane and must be given careful attention. When under way, traveling at from 140 to 200 miles an hour, the speed of 65 the aeroplane is so much greater than the ve-

locity of the wind that only in case of a severe storm is it necessary to leave the course and tack on account of the wind.

It is apparent that the embodiment of the invention which I have described in detail 70 possesses all the features of advantage enumerated as desirable in the statement of the invention and the above description. It is also evident that numerous changes in the details of construction and in the combination and arrangement of parts may be resorted to, without departing from the spirit and scope of the invention as hereinafter claimed, 75 without sacrificing any of its advantages.

What I claim is:—

1. In an aeroplane or similar craft, a hull, 80 two parallel rows of propulsion units supported by and above the hull, each propulsion unit being swiveled upon a vertical axis and including an air propeller having a horizontal axis; and means for simultaneously rotating the units of the two rows in respectively the same direction and to equal rotational extents about their swiveling axes.

2. In an aeroplane or similar craft, an assemblage as per claim 1, in which the two rows of propulsion units extend longitudinally of the hull and respectively at opposite sides of the vertical longitudinal medial plane of the hull.

3. In an aeroplane or similar craft, an assemblage as per claim 1, in which the two rows of propulsion units extend longitudinally of the hull and respectively at opposite sides of the vertical longitudinal medial plane of the 95 hull and at equal distances from the said plane.

4. In an aeroplane or similar craft, an assemblage as per claim 1, in which the steering means include two control shafts each extending adjacent to the propulsion units of one row, gearing connecting each shaft with the units adjacent to it, and a mechanism interposed between the two control shafts for simultaneously rotating the two shafts in respectively opposite directions.

5. In an aeroplane or similar craft, an assemblage as per claim 1, in which the steering means include two control shafts each extending adjacent to the propulsion units of one row, gearing connecting each shaft with the units adjacent to it, and a mechanism interposed between the two control shafts for simultaneously rotating the two shafts in respectively opposite directions and to the same 115 rotational extent.

6. In an aeroplane or similar craft, a hull, two parallel rows of propulsion units supported by and above the hull, each propulsion unit being swiveled upon a vertical axis and including an air propeller having a horizontal axis; and means for simultaneously rotating the units of the two rows in respectively the same direction and to equal rotational extents about their swiveling axes; the said 125

means including a shaft and gear assembly arranged for continuously maintaining a parallel relation between the axes of all of the air propellers of the propulsion units in the said two rows.

7. In an aeroship or similar craft, two parallel and spaced hulls, superstructures spanning the space between the two hulls, masts rising from the superstructures and disposed respectively in the vertical and longitudinal medial planes of the two hulls, wings carried by each mast, and air propellers carried by the superstructures, the air propellers being disposed in rows respectively at opposite sides of each of the masts, and means connecting the air propellers of each row for simultaneously and bodily rotating them about vertical axes.

8. In an aeroship or similar craft, a hull, two parallel rows of air resisting propulsion units supported above the hull, the units in each row facing in the same direction and being substantially uniformly spaced over the major portion of the length of the hull, each unit being swiveled on a vertical axis and the swiveling axes of the units in each row being in a common plane; two parallel and rotatable control shafts respectively adjacent to the two rows of units, common means for simultaneously rotating both control shafts, and gear mechanisms respectively positively connecting the units of each row with the control shaft adjacent to that row; the said rotating means and mechanisms being arranged for simultaneously rotating all of the said units about their swiveling axes, and for rotating the units of the said two rows in the same direction.

9. In an aeroship or similar craft, a hull, two parallel rows of propulsion units supported by and above the hull, each propulsion unit being swiveled upon a vertical axis and including an air propeller having a horizontal axis, the two rows of units disposed symmetrically about the longitudinal plane of the hull, the said propulsion units arranged in forward, aft and intermediate groups, steering means for simultaneously rotating the pair of forward units in the same direction and to equal rotational extents about their swiveling axes, steering means for simultaneously rotating the pair of aft units in the same direction and to equal rotational extents about their swiveling axes and in opposite direction to the rotation of the aforesaid forward steering means, and means for simultaneously rotating all units of the intermediate group in the same direction and to equal rotational extents about their swiveling axes, substantially as specified.

In testimony whereof I affix my signature.
SAMUEL E. HITT.
